US00RE48566E

(19) **United States**
 (12) **Reissued Patent**
 MacKay et al.

(10) **Patent Number:** **US RE48,566 E**
 (45) **Date of Reissued Patent:** **May 25, 2021**

(54) **PARKING METER**

(71) Applicant: **J.J. MacKay Canada Limited**, New Glasgow (CA)

(72) Inventors: **George Allan MacKay**, New Glasgow (CA); **James George MacKay**, New Glasgow (CA); **Adrian Ignatius O'Neil**, New Glasgow (CA); **Robert Steven Cosh**, Antigonish (CA); **Darren Scott Cameron**, New Glasgow (CA); **Gregory Emile Chauvin**, Brookside (CA); **David Andrew McMullin**, Ottawa (CA); **Michael Brown**, Ottawa (CA); **Matthew Watson**, Ottawa (CA)

(73) Assignee: **J.J. MacKay Canada Limited**, New Glasgow (CA)

(21) Appl. No.: **29/697,683**

(22) Filed: **Jul. 10, 2019**

CLAIM

The ornamental design for a parking meter, as shown and described.

DESCRIPTION

FIG. 1 is a front perspective view of a first embodiment of a parking meter;
FIG. 2 is a rear perspective view of a first embodiment of a parking meter;
FIG. 3 is a left side view of a first embodiment of a parking meter;
FIG. 4 is a front view of a first embodiment of a parking meter;
FIG. 5 is a right side view of a first embodiment of a parking meter;

FIG. 6 is a rear view of a first embodiment of a parking meter;

FIG. 7 is a top view of a first embodiment of a parking meter;

FIG. 8 is a front perspective view of a second embodiment of a parking meter;

FIG. 9 is a rear perspective view of a second embodiment of a parking meter;

FIG. 10 is a left side view of a second embodiment of a parking meter;

FIG. 11 is a front view of a second embodiment of a parking meter;

FIG. 12 is a right side view of a second embodiment of a parking meter;

FIG. 13 is a rear view of a second embodiment of a parking meter; and,

FIG. 14 is a top view of a second embodiment of a parking meter.

The broken lines showing portions of the parking meter are included for the purpose of illustrating portions of the article and form no part of the claimed design.
